UNITED STATES PATENT OFFICE.

EARL A. MUNGER, OF KALAMAZOO, MICHIGAN, ASSIGNOR TO ACME MACHINE PRODUCTS COMPANY, OF KALAMAZOO, MICHIGAN.

PUNCHING MACHINE.

Application filed May 17, 1926. Serial No. 109,611.

The main objects of this invention are:

First, to provide an improved punching machine for castellating nuts which is very simple in structure and operation and at 5 same time effective and of substantial capacity.

Second, to provide a machine for castellating nuts in which the parts are so associated and the work so supported and presented to the punch and die that the strain 10 thereon is minimized.

Third, to provide a punching machine of 15 the class described in which the slugs are automatically cleared or discharged from the work.

Objects relating to details and economies of construction and operation of my invention will definitely appear from the detailed description to follow.

20 The invention is clearly defined and pointed out in the claims.

A structure which is a preferred embodiment of my invention is clearly illustrated in the accompanying drawing, forming a 25 part of this application, in which:

Fig. 1 is a fragmentary perspective view 30 of a punching machine embodying my invention, only such parts of the machine being illustrated as are deemed necessary to illustrate my improvements.

Fig. 2 is a fragmentary view partially in horizontal section on a line corresponding to line 2—2 of Fig. 1.

Fig. 3 is a fragmentary view partially in 35 vertical section of the anvil, die and punch, a nut blank being indicated by dotted lines.

Fig. 4 is a detail view partially in horizontal section on a line corresponding to 40 line 4—4 of Fig. 3.

Fig. 5 is an end elevation of the anvil and die.

Fig. 6 is a fragmentary plan view with the work carriage in its advanced or operative position.

45 Fig. 7 is a perspective view of the work holder proper.

Fig. 8 is a detail section on a line corresponding to line 8—8 of Fig. 1 showing the arrangement of the friction brake.

50 In the drawing similar reference characters refer to similar parts throughout the several views, and the sectional views are taken looking in the direction of the little arrows at the ends of the section lines.

Referring to the drawing, 1 represents the 55 bed of a punch press, 2 the reciprocating punch head and 3 the head way.

Certain features of my improvements as 60 illustrated are adapted as an attachment, the parts being mounted on a bed plate 4 adapted to be attached to the bed 1 by means of machine screws 5.

The bed plate 4 has a way 6 therein for the work carriage 7, this carriage being 65 manually reciprocated, in the structure illustrated, by means of the lever 8 which is pivoted at 9 and connected to the carriage by means of the link 10.

The work holder 11 is rotatably supported 70 in the carriage by means of the spindle 12. This work holder is adapted to receive the hexagon head of a castellated nut blank, as 13.

Mounted in opposed relation to the carriage is an anvil 14 having a curved work 75 rest or seat 15 on its face. This anvil is supported in a block 16 having a bore there- 80 in to receive the anvil which is cylindrical in form, the anvil being held in the block by means of the set screw 17.

The die 18 has a slot 19 in its end, the die being supported in a bore 20 in the anvil to project over the seat 15 and being thus supported in operative relation to the punch 21.

85 The anvil 14 has a slot 22 registering with the slot of the die, the purpose of this being to permit the use of a punch of considerable width, thereby permitting the use of a strong and durable punch. The die is 90 secured in the anvil by means of the pin 23 arranged transversely through the same, as shown in Fig. 3.

With the parts thus arranged, the work 95 13 is presented by the carriage so that it is supported by the seat 15 with the die entering the bore of the nut. To facilitate the clearance of slugs from the die the rear wall 24 of the slot 19 is rearwardly inclined. The slugs are thus directed into and through the 100 nut into the passage 25 extending through the spindle 12 so that the slugs are discharged from the rear end of the spindle into a trough 26.

The work holder is rotated with a step by 105 step movement in synchronism with the actuation of the punch by means of a star wheel 27 on the rear end of the spindle which

coacts when the carriage is in its advanced position with the tappet 28 which is connected to the sprocket gear 29 driven from the chain 30.

5 The details of these connections are not shown as, it is believed, they will be readily understood by those skilled in the art.

To prevent overthrow, I provide a friction shoe 31 coacting with the spindle 12, 10 this friction shoe being adjustably supported by means of the set screw 32.

When the carriage is retracted, the work is automatically stripped from the die by means of the stripper rods 33, there being 15 a pair of them in the structure illustrated which are projecting from each side of the die, as shown in Fig. 4. These stripper rods are connected by the crosshead 34 at the rear of the anvil, the crosshead being engaged by the adjustable tappet 35 on the 20 arm 36 which is pivoted at 37 to the anvil supporting block and connected by the link 38 to the carriage, so that when the carriage 33 to is fully retracted, the work is ejected.

25 The blank being placed in the work holder, the carriage is advanced to position the work in proper relation to its supporting anvil and the die. These operations, in the structure illustrated, are performed manually, that 30 is, the work placed in the holder and the work advanced and retracted.

The means for controlling the operation of the punch are not illustrated as they form no part of this invention.

35 My improvements as I have embodied them in nut castellating machines are highly efficient, the work being supported so that the punches are light and strong and very durable. Also, the machine is of large capacity.

I have not attempted to illustrate or describe various modifications and adaptations which I contemplate as I believe these disclosures will enable those skilled in the art 40 to embody or adapt the same as may be desired.

Having thus described my invention, what I claim as new and desire to secure by Letters Patent is:

50 1. In a punching machine, the combination of a reciprocating punch, an anvil provided with an upwardly facing segmental work rest, a slotted die projecting from said anvil above said rest, the rear wall of the slot of 55 the die being rearwardly inclined, said anvil having a slot extending upwardly from said slot in said punch, a reciprocating work carriage adapted to position the work carried thereby upon said work rest with said die

60 entering the work, a work holder rotatably mounted on said carriage, said work holder having a spindle with a longitudinal opening permitting the discharge of slugs there-through, means for rotating said work holder comprising a star wheel on the spindle of the work holder, 65

the work holder, a tappet coacting with said star wheel when the carriage is in its advanced position, and a friction brake coacting with said work holder spindle to prevent overthrow thereof.

70 2. In a punching machine, the combination of a reciprocating punch, an anvil provided with an upwardly facing segmental work rest, a slotted die projecting from said anvil above said rest, the rear wall of the slot of 75 the die being rearwardly inclined, said anvil having a slot extending upwardly from said slot in said punch, a reciprocating work carriage adapted to position the work carried thereby upon said work rest with said die 80 entering the work, a work holder rotatably mounted on said carriage, said work holder having a spindle with a longitudinal opening permitting the discharge of slugs therethrough, and means for rotating said 85 work holder.

3. In a punching machine, the combination of a reciprocating punch, an anvil provided with an upwardly facing segmental work rest, a slotted die projecting from said anvil above said rest, the rear wall of the slot of 90 the die being rearwardly inclined, said anvil having a slot extending upwardly from said slot in said punch, a reciprocating work carriage adapted to position the work carried thereby upon said work rest with said die

95 entering the work, a work holder rotatably mounted on said carriage, said work holder having a spindle with a longitudinal opening permitting the discharge of slugs therethrough, means for rotating said work holder, 100

105 a pair of stripper rods slidably mounted in said anvil to be projecting at the sides of said die, said rods being provided with a crosshead at the rear of the anvil, 110

a pivotally mounted actuating arm provided with an adjustable tappet coacting with said crosshead, and a link connecting said arm to said carriage whereby the stripper is actuated upon the return stroke of the carriage. 115

4. In a punching machine, the combination of a reciprocating punch, an anvil having a segmental work seat, a slotted die projecting from said anvil above said work seat, a reciprocating work carriage adapted to position the work carried thereby upon said work seat with said die entering the work, a work holder rotatably mounted on said carriage, said work holder having a spindle with a longitudinal opening permitting the 120 discharge of slugs therethrough, means for rotating said work holder comprising a star wheel on the spindle of the work holder, a tappet coacting with said star wheel, and a friction brake coacting with said work holder to prevent overthrow thereof.

125 5. In a punching machine, the combination of a reciprocating punch, an anvil having a segmental work seat, a slotted die projecting from said anvil above said work seat, 130

- a reciprocating work carriage adapted to position the work carried thereby upon said work seat with said die entering the work, a work holder rotatably mounted on said carriage, said work holder having a spindle with a longitudinal opening permitting the discharge of slugs therethrough, and means for rotating said work holder. 6. In a punching machine, the combination of a reciprocating punch, an anvil having a segmental work seat, a slotted die projecting from said anvil above said work seat, a reciprocating work carriage adapted to position the work carried thereby upon said work seat with said die entering the work, a work holder rotatably mounted on said carriage, said work holder having a spindle with a longitudinal opening permitting the discharge of the work holder, a stripper 20 slidably mounted on said anvil to be projecting at the side of said die, and operating connections for the stripper to the carriage whereby the stripper is actuated upon the return stroke of the carriage. 25 7. In a punching machine, the combination of a punch, a work supporting anvil having a segmental work rest, a slotted die projecting over said rest, the rear wall of the slot of the die being rearwardly inclined, and a reciprocatingly and rotatably mounted work holder adapted to rotate the work upon said anvil in operative relation to said die and punch. 8. In a punching machine, the combination of a punch, an anvil having a work rest, a reciprocating work carriage provided with a rotating tool holder adapted to position the work upon said work rest with the die entering the work and to rotate the work upon said die and rest, means for rotating the work holder synchronized with strokes of the punch, and a stripper operatively associated with said work carriage to be actuated upon the return stroke of the carriage. 40 9. In a punching machine, the combination of a punch, an anvil having a work rest, a die projecting over said work rest, a reciprocating work carriage provided with a rotating tool holder adapted to position the work upon said work rest with the die entering the work and to rotate the work upon said die and rest, and means for rotating the work holder synchronized with strokes of the punch. 50 55

In witness whereof I have hereunto set my hand.

EARL A. MUNGER. [L.S.]
